BEACH CRAFT

Michele Ronzitti, Buffalo, N. Y.

Application April 7, 1941, Serial No. 387,319

4 Claims. (Cl. 9—1)

The present invention relates to improvements in beach craft and especially beach type boats.

An object of the invention is to provide a beach boat which provides amusement as well as beneficial exercise.

Another object of the invention is the provision of a boat which may be propelled through the water by an occupant thereof.

A further object of the invention is the provision of a boat which may be disassembled and collapsed into a relatively small compass for convenient transportation and storage.

Still another object of the invention is the provision of a self-propelled boat which is uncapsizable.

A still further object of the invention is the provision of a boat of the above character which is relatively simple and durable in construction and efficient in use.

Other objects and advantages of the invention will become apparent as the description progresses.

In the accompanying drawings forming a part of this specification and in which like numerals are employed to designate corresponding parts throughout:

Figure 1 is a longitudinal section through the boat taken on line 1—1 of Figure 2.

Figure 2 is a top plan view of the same.

Figure 3 is a similar view showing longitudinal sections of the boat in folded arrangement.

Figure 4 is a rear end view of the assembled boat.

Figure 5 is an enlarged transverse section taken on line 5—5 of Figure 2.

Figure 6 is an enlarged fragmentary section taken on line 6—6 of Figure 5.

Figure 7 is an enlarged fragmentary section taken on line 7—7 of Figure 1.

Figure 8 is a detail section taken on line 8—8 of Figure 7, and

Figure 9 is a fragmentary transverse section taken on line 9—9 of Figure 2.

Referring in detail to the drawings, wherein for the purpose of illustration is shown a preferred example of the invention, 10 generally designates each of a pair of complementary longitudinal side sections embodying a pair of parallel bars 11 and 12 formed of wood or the like having their rear ends secured to the opposed end faces of a rectangular shaped block 13 by a fastening bolt 14. The front ends of these bars are connected to a bow block 15 rabbeted at its outer side to receive the end portion of the bar 12 and having the inner bar 11 fitted against the inner face thereof. Between the inner and outer spaced face bars 11 and 12 is fitted a filler 16 of buoyant material, in the present instance a length of cork, of rectangular cross section shaped to fit between the bars. A

plurality of bolts 17 serve to fasten the filler and face bars firmly together and to fasten these bars to the front block 15. This part of sections 10 is pivotally connected at the front ends by a hinge joint 18, the straps of which are fastened to the opposed inner face bars 11 adjacent their forward extremities by bolts 19.

At the rear portions of the side sections 10 is mounted, in assembly, a transverse stern section 20 embodying a pair of superposed elongated layers 21 of cork or other suitable buoyant material having interposed therebetween a board 22 and a similar board 23 placed against the bottom face. Wood strips 24 and 24a are placed respectively on the side and end margins of the top face of this stern section and bolts 25 are extended vertically therethrough to firmly connect this structure. The boards 22 and 23 are formed to project beyond the ends of the cork layers so as to slidably engage end portions of the sections 10. Thus, the stern section 20 is slidably and detachably assembled in association with the side sections.

The stern structure is releasably fastened by means of a rod 26 pivotally connected to one of the rear blocks 13 by a pivot bolt 27 and movable into position to engage a keeper 28 on the complementary stern block, the free end portion of the rod being screw threaded and carrying a nut 29 for locking the same in engagement with the keeper.

Suspended below the plane of the boat sections 10 and 20 to support an occupant thereon is a seat 30 embodying an elongated sheet of canvas or the like folded at the edges and having rigid rods 31 fitted in the end folds. This seat is supported immediately forward of the section 20 by straps 32 looped over the side sections and tied thereon as shown to advantage at Figures 1 and 2.

In slotted bracket bars 33 fastened in opposed positions to the inner sides of the sections 10, adjacent the bow end thereof, is a cross member embodying a pair of tubular sections 34 having their inner ends threaded to a T fitting 35. The outer ends of the support sections 34 are flattened and slidably fitted in the slots of the brackets 33. To the center outlet of the T fitting 35 is connected the upper end of a depending pipe 36 which connects with the boss of a horizontally extending bearing sleeve 37. In this sleeve is rotatably mounted a horizontal propeller shaft 38 having secured on its forward end a propeller 39. The front tip portion of the shaft 38 and propeller boss are preferably covered by a removable cover cap 40 of conical shape.

A pair of rearwardly disposed slotted bracket bars 41 serve to support a pair of aligned transversely directed support members 42 having their

inner ends secured to a T fitting 43 shaped to form a vertical bearing having a bushing 44 mounted therein. This bushing rotatably supports a vertical stub shaft 45 having rotatably fitted on its upper reduced portion 46 a beveled gear 47.

The shaft 45 is formed integral with or secured in intersecting relation with an inclined shaft section 48 having a rear reduced portion 49 which is fastened in a socket 50 by a transverse pin 51. This socket is formed at the forward end of a U-shaped handle grip 52. On the shaft portion 49, between the socket 50 and the shoulder of the portion 48 is rotatably mounted a bevel pinion 53. On a forward reduced extension 54 of the shaft 45 is rotatably fitted a complementary pinion 55 having an extension sleeve 56 rotatably connected with the shaft 45 by a pin and groove connection 57, to prevent axial displacement of the pinion. The pinion 55 is formed with a forwardly projecting stem 59 upon which is fitted the inner end of a tubular connecting shaft 60 secured thereon by a transverse pin 61. The diametrically opposed pinions 53 and 55 are disposed to mesh with the bevel gear 47 having fastened in its top face a radially extending crank composed of an arm 62 and a rotary grip 63. The forward end of the tubular shaft 60 is connected with the rear end of the propeller shaft 33 through the medium of a universal joint 64.

On the forward portion of the side sections 10 are tied, by loops 65, a pair of roller carrying stirrups 66 as shown to advantage at Figures 1 and 2.

During use, an occupant assumes a position seated on the canvas seat 30 with his arms above the longitudinal side sections and his feet resting on the stirrups 66, as shown in broken lines in Figure 1. One hand of the occupant is placed to grip the handle member 52 while with the other he grasps the crank handle 63 to rotate this crank and the gear 47 to which it is attached. When the crank is rotated in one direction, in the present instance in a clockwise direction as shown at Figures 1 and 2, the propeller 39 is revolved so as to propel the boat forwardly through the water. Upon operation of the crank in the opposite direction the propeller rotation is reversed so that the boat is moved sternwards. In the assembly shown the drive mechanism is designed to impart four revolutions to the propeller for each turn of the crank, although this ratio may be varied to suit particular conditions. As best illustrated at Figure 1 the boat assumes a position on the water so that the triangularly shaped sections are partly submerged and partly above water while the seat and propeller are submerged substantially below the water level. It will also be noted that the transversely disposed stern section 20 provides a back rest for the occupant in addition to its function as a flotation element.

When the craft is to be transported or stored it is collapsed by detaching the threaded end of the rod 26 from the keeper 28 and swinging the rod horizontally sternwards to free the rear ends of the side sections 10, allowing slidable disconnection of the stern section. The propeller mechanism is also readily detached by withdrawing the ends of the transversely mounted tubular sections 34 and 42 from their slotted supports, while the seat and stirrups may be removed by untying the fastening loops.

It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I claim:

1. A collapsible manually propelled craft comprising a pair of longitudinal buoyant side sections hingedly connected at their forward ends, the said side sections being adapted to assume a V-shaped formation in assembly, a transverse buoyant section slidably fitted on the rear separated ends of the said side sections, a pivoted member for releasably fastening the rear extremities of the said side sections, a seat member suspended from the side sections immediately forward of the transverse section, a pair of foot supporting stirrups suspended from the side sections, a propeller rotatably supported on the side sections and disposed below the plane thereof, and manually operable gear mechanism for driving the said propeller.

2. A collapsible manually propelled craft comprising a pair of elongated side sections, a hinge pivotally connecting the front ends of the said sections, a rigid transverse section disposed between and slidably engaging rear regions of the said side sections, and a rod pivotally connected with the rear end portion of one of the said side sections and releasably engageable with the rear end of the complementary side section for releasably holding the rear ends of the side sections in assembly.

3. In a water craft, a buoyant body defining a center opening, a bearing member attached to and depending from the forward portion of the body, a longitudinally extending shaft journaled in the said bearing member substantially below the plane of the body, a propeller mounted on the forward end of the said shaft, a support member secured to and extending transversely in the rear region of the body, an upwardly directed stub shaft mounted on the said transverse member, a shaft extending rearwardly from the said stub shaft having a hand grip fastened thereto, a stub shaft projecting forwardly from the upstanding stub shaft, a propeller drive shaft journaled on the forwardly extending stub shaft and connected to the rear end of the propeller shaft, a pair of bevelled gears rotatably mounted on the rearwardly directed shaft and fixed to the propeller drive shaft respectively, a drive gear rotatably mounted on the upper portion of the upstanding stub shaft meshing with the said pinions, and a hand crank attached to the said drive gear for manual operation of the propeller.

4. A craft of the character described comprising a pair of buoyant side sections pivotally connected at their forward ends, a transverse section detachably connected with the rear end portions of the said side sections, means for releasably fastening the said sections in craft forming assembly, a seat member attached to and extending between the side sections forward of the transverse section, a pair of foot supporting elements attached to the said side sections, a propeller rotatably supported on the said side sections, and manually operable gear mechanism for driving the said propeller.
